George F. Landgraf, Pittsburgh, Pa., assignor to Trion, Inc., McKees Rocks, Pa., a corporation of Pennsylvania

Filed Jan. 22, 1957, Ser. No. 635,209

3 Claims. (Cl. 117—93)

My inventions relate to electrostatic coating apparatus, more particularly, apparatus for coating moving articles. It is especially designed for coating a continuous strip which moves at varying speeds:

My inventions are particularly useful for applying a coating of oil to a continuous steel strip which has been plated with tin such as is rolled in steel mills and commonly referred to as tin strip. Therefore, my inventions will be described with particular reference to this product, although it is to be understood that they are useful in coating continuously moving strips of other metals and other moving objects.

In the steel industry, it has always been the practice to coat so-called tin plate with a coating of vegetable oil, such as cottonseed oil or one of the synthetic substitutes dibutyl sebacate or dioctyl sebacate, to protect the surface of the strip from being marred or scratched. Tin plate is made in the steel industry from long continuous coils of steel strip and, in this method of manufacture, applying oil to the finished plated strip is difficult because the strip moves at varying rates of speed.

The problem has been aggravated by increasing emphasis on close control of the quantity of oil or coating material applied to the surface of the strip. Close control is emphasized to provide sufficient protection for the tin plated surface without excessive oil which would interfere with subsequent processing operations, such as soldering or lithographing. This control has become so close that present specifications call for as little as 0.05 gram of oil per base box of tin plate. The closeness of this control can be appreciated when it is realized that a base box of tin plate is 218 square feet of tin plate which must be uniformly coated on both sides.

Since the advent of the present process of making tin plate in long continuous strips, it has been the practice to apply the oil to the moving strip by electrostatic deposition. That is, a high electrostatic field has been created on both sides of the continuously moving strip by electrodes spaced away from and on opposite sides of the strip and by spraying the coating material in the form of a mist between the strip and the electrodes. The mist is electrostatically charged by the electrodes and the charged mist particles are attracted to and deposited onto the strip by the electrostatic field created between the electrodes and the strip and thereby the efficiency of the coating process is greatly improved. This coating method has not, however, solved the problem of controlling the amount of coating material applied to the strip because the strip moves at frequently varying rates of speed. For example, the strip in a modern tin mill may move at rates varying from 200 feet to 2400 feet a minute and the line occasionally may be stopped.

Various expedients for regulating the amount of coating material applied to the strip in accordance with the speed of the strip have been attempted, for example, by regulating the air pressure to a spray gun which sprays the coating material into the electrostatic field in accordance with the rate of speed of the strip. None of these attempts, however, has been successful in that they have not provided sufficiently close control of the amount of oil applied to meet present requirements.

In accordance with my invention, I create a fine mist

2

aspirators. The mist is then carried into a charging chamber having an ionizing electrode from which it passes to the coating zone for the strip, i.e., a zone in which an electrostatic field is created which forces the particles in the mist towards the continuously moving strip. I thus employ two separate electrostatic stages; in one, the mist particles are ionized or charged and, in the second, the particles are deposited by the electrostatic field on the strip without further ionization.

As noted, I create a very dense fine mist of coating material in fog chambers using multiple conventional aspirators. Compressed air supplied to the aspirators displaces some mist from the fog chambers, carrying it into the ionizing or charging chambers at relatively low velocity. The mist moving slowly through the charging chamber under these conditions is not only charged but has time to be completely precipitated on the walls of the charging chambers and drains back into the oil reservoirs in the bottom of the fog chambers. Thus, under the above conditions when only the air supplied to the aspirators is introduced into the fog chambers, no mist ever gets past the charging chambers to be deposited. In order to get some charged mist through the ionizer to be deposited on the tin strip in the separate electrostatic field of the coating zone, it is necessary to increase the velocity of the mist through the ionizer. The faster the mist travels through the ionizer, the less time is allowed for precipitation on the walls of the ionizing chamber and, therefore, the more charged mist forced into the coating zone to be deposited on the tin strip. To effect this increased velocity, secondary air is introduced into the fog chambers, thus displacing the mist more rapidly. I have found experimentally that under the above described conditions the amount of charged mist delivered to the coating zone and deposited on the tin strip bears essentially a linear relation to the rate of flow of secondary air. Therefore, by controlling the rate of flow of secondary air in accordance with the speed of the strip being coated, a uniform weight of oil per unit area of strip will be deposited.

In the accompanying drawings, I have illustrated certain presently preferred embodiments of my inventions, in which:

FIGURE 1 is a partial side view of my apparatus;
FIGURE 2 is an end view of the apparatus of FIGURE 1;

FIGURE 3 is a partial vertical section on the lines III—III of FIGURE 2 but to a larger scale;

FIGURE 4 is a view similar to FIGURE 3 but showing only one-half of the apparatus and on a still larger scale;

FIGURE 5 is a section along the lines V—V of FIGURE 4;

FIGURE 6 is a diagrammatic showing of the apparatus which I employ for regulating the flow of secondary air in accordance with the speed of the strip.

Referring to FIGURES 1 and 2, the strip 7 to be coated is led under a guide roll 8 between two fog chambers 9 and into a coating chamber 10. After coating, the strip passes out through the top of the coating chamber.

FIGURE 3 shows the construction of the two fog chambers 9, which are placed one on each side of the path of movement of the strip. Each fog chamber 9 is in the form of a tank generally rectangular in section and having a length approximating the width of the widest strip to be coated. Each chamber is parallel to the surface of the strip but extends lengthwise at right angles to the path of movement of the strip.

Each chamber has an outside vertically extending wall 11, a bottom 12, and an inner wall 13 which slopes outwardly from the inner edge of the bottom wall towards the path of travel of the strip, then vertically for a short

distance parallel to the path of travel of the strip. Each chamber has a top wall 14 which extends horizontally in from the top of the outer side wall 11 and then slopes inwardly and downwardly towards the top of the inner side wall 13 to form a base 15 for a charging chamber, designated generally by the reference numeral 16, from which mists of ionized particles of coating material pass into the coating zone 17 which is within the coating chamber 10.

The bottom and the lower portions of the side walls of each fog chamber form reservoirs for the liquid coating material and each fog chamber has conventional aspirators 18 which draw liquid coating material up from a reservoir, atomize it, and spray it in fine particles against the inner walls 13 of the fog chambers. The atomizers are supplied with compressed air through pipes 19 from a common header 20 connected to a source of compressed air which is not shown. As shown in FIGURE 1, each fog chamber has several aspirators spaced from each other along the length of the chamber.

As noted, the aspirators 18 are directed against the inner walls 13 of the fog chambers, with the result that large droplets of coating material impinge upon and adhere to the walls 13 and drop back into the reservoir of coating material at the bottom of the fog chambers. Therefore, only very fine air-borne mist passes from the fog chambers into the charging chambers 16. To further insure the removal of large droplets and to create a turbulence in the fog chambers, I provide in each a baffle 21 which extends outwardly and downwardly from a point adjacent the top of the side wall 13, leaving only a relatively small passageway 22 between the outer edge of the baffle and the outside side wall 11.

The construction of the chambers 16 will be later described. It should be noted here that each carries fine ionizing wires 23 (see FIGURE 5) which are supported on supports 24 at each end of the chamber and which extend the full length of the chambers. It should also be noted that at the bottom of each chamber there is a narrow passageway 25 which also extends the length of the chamber and through which mist from a fog chamber passes into the chambers 16.

A high potential unidirectional current is connected to the ionizing wires within each chamber 16. These wires then react with the sides of the chamber, causing ions to flow from the wires to the side walls whereby the particles of mist of coating material are ionized before they reach the coating zone 17.

Within each charging chamber, there exists a turbulent electrostatic field surrounding the ionizing wires which tends to precipitate the oil mist onto the walls of the chamber, from whence the material refluxes back into a fog chamber. When the velocity of the mist in the charging chamber is created solely by the air supplied to the aspirators 18, practically all of the mist will be precipitated in the charging chambers and returned to the fog chambers and thence to the reservoirs of fluid at the bottom of the chambers. To drive the mist of coating material out of the chambers 16, I provide an additional stream of gas (preferably air) to the fog chambers through conduits 26. The velocity of the air supplied through the conduits 26 is adjusted so that it will move the mist particles with sufficient speed through the chambers 16 that a portion of them will not be precipitated on the side walls of the conduit. They will, therefore, pass into the coating zone 17.

Referring to FIGURE 1, it will be seen that air to the conduits 26 is supplied by a conventional blower 27. Uniform distribution of air supplied through the conduits 26 to the fog chamber is obtained by adjustable plate valves or shutters 28 which may be adjusted to vary the size of the opening 29 between the conduits 26 and the side walls 11 of the fog chambers. As has been noted, the volume of air through the conduits 26 is adjusted in accordance with the speed of the strip. This is accom-

plished by adjusting a butterfly valve 30 positioned in the conduits 26 adjacent the blower 27. The control of the valve 30 will be later described.

When the mist of coating material passes from the charging chamber 16 into the coating zone 17, the mist particles pass into a high potential electrostatic field created between the strip 7 and two plate electrodes 31 equally spaced from the strip on opposite sides of the strip and extending parallel to the path of travel of the strip in the coating chamber 10. The plates 31 are mounted within the coating chamber 10 in a conventional manner by insulators 32. The plates 31 have the same polarity as the ionizing wires in the chambers 16 and maintain a high potential with respect to the strip. Oil mist passing into the coating zone from the charging chambers 16 is, therefore, attracted to and deposited on the moving tin strip.

FIGURE 4 shows one of the charging chambers 16. Each chamber is formed from two elongated rectangular shaped plates 33 whose length is slightly greater than the width of the maximum width of strip to be coated in the apparatus. The plates extend across the strip and at right angles to the path of movement of the strip. The lower portions 34 of the plates are bent inwardly 25 towards each other to form a narrow rectangular shaped passageway 25 through which mist passes into the chambers 16. The lower ends of the inclined portions 34 of the plates are bent inwardly to form flanges 35 extending at right angles to the plane of the major portion of the plates. The flanges 35 rest on plates 36 which extend the full length of the plates 33 and which extend across the plates 33 at each end to support the plates 33 in proper position and also to support insulators 37 for posts 24 for ionizing wires which, as noted, extend lengthwise within the chambers 16.

The charging chambers 16 are supported below the coating chamber 10 by plates 38 which extend first inwardly from the sides of the coating chamber and then outwardly and downwardly to the top plates 15 of the fog chambers 9. The charging chambers are also supported by flat plates 39 which are mounted on the top plates 15 at right angles thereto. Angles 40 having a flange extending inwardly from the plates 38 and 39 are spaced a short distance above the top plates 15 so as to form narrow slots 41 in which the outer edges of the base plates 36 may slide. The charging chambers 16 can be quickly and easily removed by sliding them lengthwise out of an end wall of the coating chamber because of this sliding support arrangement.

The charging chambers 16 each have mechanism for adjusting the effective width of the slot 25 at the base of the charging chambers so as to vary the width of the path of mist and air which flows through the chambers 16 in accordance with the width of the strip being coated. Immediately below each slot 25 in the bases of the charging chambers, there is an elongated slot 42 in the top plate 15 of each fog chamber. U-shaped channels 43 extend along both edges of the slots 42 for the full length of the slots. Two strips 44 and 45 having the same width as the bottom flanges of the channels 43 are secured to the channels in line with the bottom flanges, as shown in FIGURE 4. The strips 45 have notches 46 cut out in their inner corners adjacent the strips 44 to form opposed narrow slots in which shutters 47 extending inwardly from each end of the fog chambers may slide. The shutters 47 each have racks 48 which mesh with pinions 49. The pinions 49 are turned by means of a hand wheel 50 which is connected to the pinions 49 by gearing 51 and shafts 52 (see FIGURES 1 and 2).

Turning the hand wheel 50, therefore, will move the shutters 47 inwardly and outwardly in the slots formed by the notches 46. As the shutters move outwardly, they extend out through the ends of the fog chambers into rectangular shaped casings 53.

It was mentioned that the chambers 16 can be removed

from the apparatus by sliding them lengthwise in the slot between the angles 40 and the top plates 15 of the fog chambers 9 (see FIGURE 4). They are thus removed out of the end of the apparatus which appears in FIGURE 2. The opposite end of the apparatus carries means for electrically connecting the ionizing wires in the charging chambers 16. This is shown in FIGURE 5.

The end of the casing opposite to the end from which the charging chambers are withdrawn has openings above the fog chambers which are in line with the charging chambers when they are in operating position. These openings are closed by cover plates 54 and bolting plates 55. The connections between the end of the casing 10, the cover plates 54, and the bolting plates 55 are sealed by a gasket 56. A junction box 57 is secured to the outside of the plates 54 and 55. It carries a hollow conically shaped insulator 58 which is held to the cover plate 54 by a collar 59 bolted to the plates 54 and 55. The wide end of the insulator is next to the cover plate 54. The small end of the insulator carries a jack plug socket 60 which, in turn, has a bolt 61 to which a high voltage wire can be connected.

Referring to FIGURE 5, the post support 24 for the ionizing wires 23 has soldered to it at its base an elongated metal rod 62 which extends at right angles to the post 24 and parallel to the center line of the charging chamber 16. The other end of the rod 62 forms a jack 63 adapted to fit into the socket 60. The post 62 except for the jack 63 is surrounded by a glass tube 64 which is spaced from the rod 62 by rubber washers 65.

It will be noted from FIGURE 5 that, when a chamber 16 is slid along its support above a fog chamber, the post 62 slides into the socket 60 in the junction box and thus a connection for the ionizing wires is automatically made at the same time the chamber is slid into operative position. Holes 66 and 67 are formed in the plates 54 and 55, respectively, so as to allow the rod 62 to pass into the insulator 58 in the socket 60.

As has been pointed out, an important feature of my invention lies in the concept of regulating the amount of coating material supplied to the strip by adjusting according to the speed of the strip the volume of air supplied to the fog chambers independently of the air supplied to the aspirators. FIGURE 6 shows the apparatus for thus regulating the flow of air to the fog chambers. The figure is diagrammatic because all of the components used in the control are conventional. A tachometer generator 68 is placed where it can be actuated by a rotating part which rotates in accordance with the speed of the strip, for example, the axle 69 of the roll 8 which guides the strip into the coating apparatus. The tachometer generator sends an electric signal which is proportional to the speed of the strip to an electropneumatic link receiver 70.

The receiver 70 adjusts the pressure of air in the line 71 which is supplied by a line 72 connected to a source of compressed air, not shown. The line 71 leads to a ratio relay 73 which has a beam mounted on a movable fulcrum. One end of the beam is actuated by the air pressure in the line 71. The other end of the beam sends a signal, i.e., air pressure, through a line 74 to a sending head 75. The fulcrum in the ratio relay 73 is manually adjusted by the operator to set the device for a predetermined ratio of strip speed to volume of air and the relay sends a signal to the sending head 75, which signal corresponds to the amount of air which should be supplied for a particular speed of the strip in accordance with the predetermined ratio.

The sending head 75 integrates the flow of air through the conduits 26 with the signal received from the relay 73 and, in turn, sends a signal through a line 76 to a pneumatic cylinder 77 which, in turn, opens and closes the butterfly valve 30. The sending head 75 measures the flow through the conduit 26 by measuring the difference in pressure across a fixed orifice 78 positioned in the con-

duit 26 just beyond the valve 30. Lines 79 and 80 connect the sending head across the orifice plate 78.

In an actual installation and operation of my inventions, I have found that the amount of oil or coating material supplied to the strip is directly proportional to the volume of air supplied to the fog chambers separate from that supplied through the aspirators. By the controls which I have just described, it is possible to regulate the volume of air in accordance with the speed of the strip. The result is that the volume of oil supplied to the strip is closely regulated in accordance with the speed of the strip. I have found that my inventions provide a much closer control for the amount of oil supplied to the strip in a conventional continuous tin line than has heretofore been possible.

The structure of the charging chambers for delivering oil into the coating zone whereby they can be quickly removed and replaced in the event of breakage of the ionizing wires is also a feature of some importance. The ionizing wires have to be replaced at intervals and it is important that this be done quickly because of the great cost loss involved in stopping a continuous tin strip line. For example, it has been estimated that stopping a tin line in a modern strip mill costs \$100 a minute. The importance of being able to replace the ionizing wires quickly can, therefore, be appreciated.

While I have described certain presently preferred embodiments of my inventions, it is to be understood that they may be otherwise embodied within the scope of the appended claims.

I claim:

1. Electrostatic coating apparatus comprising a coating chamber, means for moving the article through said chamber, at least one electrode spaced from the path of travel of the article through the coating chamber, means for creating a unidirectional electrostatic field between the article and said electrode as the article passes through said chamber, at least one fog chamber, means in said fog chamber for creating a mist of coating material, a charging chamber leading from said fog chamber to the coating chamber, means in the charging chamber for creating an electrostatic field through which mist of the coating material passes from the fog chamber to the coating chamber, a high voltage source for said electrostatic field in the charging chamber, means independent of said mist generating means for supplying a flowing gas to the fog chamber to carry the mist of coating material from the fog chamber through the charging chamber to the coating zone, and control means for regulating only said supply of flowing gas to the fog chamber in proportion to the rate of movement of the article to be coated through the coating chamber.

2. Electrostatic coating apparatus as described in claim 1 in which the charging chamber has an entry opening connected to the fog chamber, an exit opening leading to the coating chamber, at least one electrode spaced from the walls of the chamber and between said openings for creating with said walls, a high-potential electrostatic field, and a source of high potential for creating said field.

3. A method of coating an article comprising moving the article through an electrostatic field extending substantially at right angles to the path of movement of the article, forming a mist of particles of a coating material and maintaining the mist out of contact with the article, supplying a flow of gas separate from the mist forming means to move the mist from the position where it is formed to a position adjacent the article in the first mentioned electrostatic field, electrostatically charging all of the mist particles in an electrostatic field removed from the path of movement of the article, as they move towards the article, and controlling the rate at which the mist moves to the article by regulating only the rate of flow of said gas in accordance with the speed of movement of the article.
